(57) **CLAIM**

The ornamental design for a dental scanner, as shown and described.

DESCRIPTION

FIG. 1 is a perspective view of the dental scanner showing the entire shape of the design;

FIG. 2 is an enlarged front view thereof;

FIG. 3 is an enlarged rear view thereof;

FIG. 4 is a left side view thereof;

FIG. 5 is a right side view thereof;

FIG. 6 is a top view thereof;

FIG. 7 is a bottom view thereof;

FIG. 8 and FIG. 9 are enlarged perspective views that express the part to be protected; and,

FIG. 10 is an enlarged view that shows the state of use when a battery is inserted in the bottom of the dental scanner. The broken lines in the drawings are included for the purpose of illustrating portions and environmental elements of the dental scanner and form no part of the claimed design.
